UNITED STATES PATENT OFFICE

NILES PEEBLES, OF DALLAS, TEXAS, ASSIGNOR OF ONE-HAIF TO B. A. MARRINER, OF BATON ROUGE, LOUISIANA

ELEVATOR

Application filed October 2, 1929. Serial No. 396,828.

The invention relates to an elevator such as is used in well drilling rigs to raise the pipe or tubing during the operations.

It is usual in well drilling rigs to have a cable threaded from the draw works over the crown block and down to the traveling block. By means of this cable the traveling block may be raised or lowered as desired. Various tools have been designed to be carried by the traveling block. The present invention relates to one of these tools and is known as an elevator which comprises a construction or mechanism adapted to connect around a piece of pipe that it may be raised or lowered by the movement of the traveling block.

It is one of the objects of the present invention to devise an elevator having a latch thereon which will normally remain in the open position.

Another object of the invention is to devise an elevator wherein the jaws may be locked in the closed position due to the fact that a pipe has been engaged by the jaws.

Still another object of the invention is to devise an elevator having rounded corners on the upper and lower sides to prevent its catching on any obstruction while it is being raised or lowered.

Still another object of the invention is to devise a pair of ears or lugs of novel construction to retain the bails by which the elevator is supported.

It is also an object of the invention to devise a novel link construction which will not readily become misplaced with respect to the elevator jaws.

Still another object of the invention is to devise a handle upon each of the jaw members which is of such construction that it may be conveniently grasped by the operator.

Still another object of the invention is to eliminate the use of bolts and nuts which project from the face of the elevator.

I also contemplate as an object of the invention the provision of a latch member which will be actuated by the closing movement of the jaw members when a pipe is being engaged.

Other and further objects of my invention will be readily apparent to those skilled in the art to which my invention appertains when the following description is considered in connection with the accompanying drawings wherein:

Fig. 1 is a top plan view of an elevator constructed in accordance with my invention and showing certain parts in section for purposes of illustrating the latching mechanism.

Fig. 2 is a side elevation showing the elevator with the supporting links removed therefrom.

Fig. 3 is a perspective view of the elevator with the jaws in open position and showing the construction of the elevator and the supporting links therefor.

Fig. 4 is a front elevation of the elevator in closed position and showing one of the handles broken away so that the construction of the latching mechanism may be observed.

Fig. 5 is a central vertical section of the spring pressed bolt which serves to operate the latch.

By having reference to Fig. 3 I have shown a member indicated generally at 1. This member may be the lower portion of a C-link or of the traveling hook which is carried by the traveling block. Upon this link or hook 1, I have shown a pair of links or bails at 2. These bails are somewhat different from the ordinary construction and have a small opening 3 formed at the upper end thereof to receive the C-link or traveling hook 1. These bails below the opening 3 are formed of an integral piece of metal which may assume any desired form, but is of sufficient cross section to withstand the stresses which may be encountered. The lower end of the links are enlarged at 4 and provided with an opening 5, which may be of considerably larger area than the opening 3. While I have shown a particular type of link in this embodiment of my invention, I do not desire to be limited to this precise construction as obviously the ordinary type of bail may be

used in combination with my improved elevator.

The elevator has been indicated generally at 7 and comprises a pair of co-operating jaws 8 and 9. These jaws are formed to pivot upon a pin 11, as a hinge, so that they may be moved to the position of either Fig. 1 or Fig. 3. These jaws 8 and 9 are identical with the exception of the construction forming the hinge portion at 12 and the latching mechanism indicated generally at 14.

The construction of the jaw member may be best seen by the illustration of the top view shown in Fig. 1 and the side view shown at Fig. 4. Each of the jaws has a substantially semi-circular body portion 15, having a handle 16 on the forward side thereof. This handle 16 is preferably formed integral with the body portion 15 and extends forwardly and slightly outwardly as seen in Fig. 1. This handle is rounded at the top and bottom as seen in Fig. 2 at 17 and 18. With this construction as the elevator is being raised or lowered in the derrick any obstructions will slide over the rounded portion of the handle and damage to the elevator or derrick is avoided. Particular attention is directed to the large size of the handle which makes it convenient for the operator to grasp. With elevators now in use the handle comprises a single bar extending horizontally with a knob on the end thereof. It is practically impossible for the derrick man to manipulate each elevator unless it is at a position directly in front of him and about chest high. The handles now in use constitute a hazard also in that it will catch beneath the bracing, finger board or other structures while being raised or lowered. Also it may catch in the safety belt or garment of the derrick man and cause injury. With the improved enlarged rounded handles here shown it is possible for the operator to grasp the handles in any position within his reach and they are of such size that he may obtain a firm hold on either the top, bottom or front. Another advantage of these enlarged handles is that it forms a protective guard for the latching mechanism.

Fig. 4 shows the arrangement of the upper lug or ear 20 and the lower ear 21. These are preferably formed integral with the body portion 15 of the jaw and extend outwardly and downwardly. They are rounded as seen in Figs. 2 and 3, so that they will avoid obstructions in the derrick. It should be noted that the upper ear 20 provides an upwardly inclined shoulder 23. This shoulder 23 forms a curve with the upper face 24 of the lower ear 21 so that the lower portion 4 of the bail will remain loose and free from the elevator body at all times. The outer surface of the elevator body 15 is

shown as circular at 25 but is slightly out away at 26 between the ears 20 and 21 in order to accommodate the bail 2. In this manner the point of contact of the bail and the elevator body is as close to the center line as is possible and an almost direct pull is therefore exerted which will tend to retain the elevator jaws in a closed position.

I have shown a bolt 30 as having been inserted into an opening 31 in the ear 20 and being seated in a socket 32 in the ear 21. In this manner as soon as the bail 2 has been inserted between the ears the bolt 30 may be dropped in place. I have shown a lockpin 33 as a means of preventing misplacement of bolt 30. It is obvious that any other desired means such as threading the bolt 30 through the ear 20 may be employed. It should be noted however that the pin 30 does not extend through the lower side of ear 21 and that no portion of the pin extends outwardly from the ears. In a great many constructions now in general use a bolt and nut are used in lieu of the bolt 30 here shown and considerable objection has been found to this construction as the nut becomes misplaced and the bolt head catches upon obstructions in the derrick. I have shown a lug 35 formed upon the forward face of one of the jaws and an aperture 36 formed in the co-operating jaw. This lug 35 serves as a dowel to insure an alignment of the two jaws when they are in a closed position.

When the elevator is to be fastened about a piece of pipe or tubing to be moved the operator grasps the handles 16, which will normally be in position shown in Figure 3. He then presses the jaws about the pipe or tube and moves them to the closed position shown in Fig. 1. It is very important that once the elevator is latched about the pipe that it remain positively locked, as many accidents have occurred due to the fact that the elevator became unlatched and allowed a string of pipe or tubing to fall into the well. In order to insure that the latch will remain in a closed position while the pipe is engaged in the elevator, I have provided a latching mechanism which includes a latch 40, shown in front elevation in Fig. 4 and in section in Fig. 1. This latch comprises a substantially rectangular body, having a central opening 41 therein. A pivot pin 42 is shown as passing through the handle 16 in a position spaced from the body 15 of the jaw a sufficient distance to permit the latch to pivot through a small angle. It will be noted that the latch is thickened to receive the bolt. The bolt 42 may be retained in the handle by any desired means but I have shown a locking pin 43 which is similar to pin 33 previously described. A spring 45 is shown as being coiled about bolt 42 and having one end

engaging the body of the jaw 15 and the opposite end engaging the latch 40. This spring is so arranged that it will normally tend to keep the latch in open position or the position illustrated in Fig. 1. A lug 46 is carried by the jaw 9 and is shown as projecting from the front side thereof in a manner to be received in the opening 41 of the latch. Thus if pressure is exerted upon the latch 40 it may pass down over the lug 46 and thereby maintain the two jaw members in a closed position.

In order that the latch 40 may act automatically and be positively retained in a closed position, I have shown a spring pressed bolt 50. This bolt is shown as comprising a sleeve 51, a head 52, a spring 53 and cap 54. The sleeve 51 is placed in a radially extended opening 55, which is formed in one of the jaw members 15. The bolt is best seen in Fig. 5. When it is once placed in opening 55 the head 52 will extend inwardly beyond the inner face 56 of the elevator jaws and the head 54 will extend beyond the outer face of the jaw but will underlie the end 58 of the latch member 40. The normal position of the latch and spring pressed bolt will be that shown in Fig. 1. However, when a pipe is engaged and the jaws 8 and 9 closed about the pipe the outer surface of the pipe will obviously engage against the head 52 of the bolt 50. The spring 53 may be quite strong and will normally prevent the inward movement of the head 52. In this manner it will be seen that when pressure is exerted upon the head 52 that the sleeve 51 and cap 54 will move outwardly with respect to the jaw body 15. This outward movement will cause the cap 54 to engage the portion 58 of the latch member and overcome the resistance of the spring 45 so as to cause the latch to pivot about the pin 42 in this manner the end 59 will pass downwardly over the lug 46. Therefore, so long as a pipe is engaged by the elevator jaws the latch 40 will remain in closed position and prevent the jaws from moving to the open position. The latch will work automatically as soon as the jaws are clamped about a section of pipe. When it is desired to remove the latch it is only necessary for the operator to move his hand inwardly from the handle 16 and catch end 59 of the latch with his finger. By exerting a pull of the latch the tension of the spring 53 will be overcome and the latch may be raised to a position to release the lug 46. It is obvious that the jaws may then be moved to an open position and the elevator released at the will of the operator.

I have shown the cap 54 as being retained within the sleeve 51 by means of a pin 60. It is obvious that this cap may be threaded into position, or welded, in lieu

of the pin 60, if desired. The cap 54 is shown as being of a larger diameter than the sleeve 51 and in this manner the bolt is prevented from moving inwardly with respect to the jaw member. The latch 40 obviously prevents removal or displacement of the bolt 50.

The particular advantages of the present elevator include the enlarged protective handles, the elimination of the projecting nuts and bolts and the rounded arrangement of the entire elevator as well as the normally open latch which is held in extended position by the spring 45. Thus no amount of jarring or closing of the jaws will cause the latch to lock so that even if the jaws swing together they will not latch unless they are clamped about a pipe and the bolt 52 compressed.

While I have shown and described what I believe to be practical construction of my invention, I do not desire to be limited to the precise structure illustrated, as it is obvious that various alterations may be made therein without departing from the spirit of the invention set forth in the appended claims.

Having described my invention what I desire to secure by Letters Patent is:—

1. In combination with an elevator, a latching mechanism therefor including a pivotal latch member, a lug adapted to be engaged by said latch in closed position, and means to normally retain said member in unlatched position, said means including a spring surrounding a bolt upon which said member is pivoted and engaging both the body of the elevator and said latch member.

2. A latching mechanism for pipe elevators including a pivoted latch member, means to retain said member in unlatched position, and additional means for closing said latch when the elevator is engaged about a pipe, said additional means including a spring pressed bolt slideable radially in the body of the elevator.

3. In combination with a pipe elevator having a pair of semi circular jaw members, a latching mechanism, means carried by one of said jaw members to normally retain said mechanism in unlatched position, and additional means to move said mechanism to latched position when said members are engaged about a pipe.

4. A pipe elevator including in combination a pair of cooperating jaw members hinged together at one side, and automatic latching mechanism carried by one of said members and operable upon said members being closed about a pipe, said mechanism including a spring pressed bolt projecting from the inner and outer faces of one of said members, a latch pivoted to said member and adapted to be engaged by said bolt when said bolt is moved by engagement with

the pipe upon closing of said jaw members.

5. A pipe elevator comprising a pair of hinged jaws, one of said jaws having a latch lug, a latch pivoted on the outer jaw and adapted to engage the lug, a spring urging the latch out of latching position, and a spring pressed member slidable in the latch jaw and engaging the latch.

6. A latching mechanism for elevators including a single latch member pivoted intermediate its ends, a spring rocking the latch into an unlatching position, and means having one end exposed to the pipe and the other end underlying the latch for over-
10 coming the spring and swinging the latch into locking position when engaged with a pipe.

7. In combination with an elevator, a latching mechanism therefor including a pivotal latch member, a lug adapted to be engaged by said latch member in closed position means normally holding said latch member outwardly of the lug when the jaws of the elevator are closed, and means
20 carried by the elevator in the path of the pipe for swinging the latch into latching engagement with the lug.

8. In combination with an elevator, a lug on one jaw of the elevator, a pivotal latch on the other jaw of the elevator, means for automatically displacing the latch when the jaws are open to reduce its protrusion into the path of the pipe, and additional means engaged by the pipe when the jaws are
30 closed for swinging the latch into latching engagement with the lug.

9. A pipe elevator comprising, a pair of hinged jaws, one of said jaws having a latch lug, a latch pivoted on the other jaw and
40 adapted to engage the lug, a spring urging the latch out of latching engagement with the lug, and a radial sliding bolt mounted in one of the jaws in the path of the pipe for engaging and swinging the latch into latching
45 position when displaced.

10. An elevator as set forth in claim 9, in which the sliding bolt is yieldable while in engagement with the pipe, whereby the latch may be manually disengaged from the lug.

50 11. In combination with an elevator comprising a pair of hinged jaws, a latch lug on one of the jaws, a latch lever pivoted intermediate its ends on the other jaw and having one end arranged for engagement
55 with the lug; a radially slidable bolt in the jaw carrying the latch engaging the opposite end of the latch; and a spring engaged with the latch normally holding its latching end out of engagement with the lug and
60 its opposite end in engagement with the bolt.

In testimony whereof I hereunto affix my signature this 25th day of September, A. D., 1929.
